[57] CLAIM

The ornamental design for an insert for agricultural applicator knife, substantially as shown and described.

DESCRIPTION

FIG. 1 is a side elevation view of the insert for agricultural applicator knife embodying our new design.

FIG. 2 is an end elevation view thereof.

FIG. 3 is a view in elevation of the end opposite that which is shown in FIG. 2.

FIG. 4 is a bottom plan view thereof.

FIG. 5 is a top plan view thereof.
